UNITED STATES PATENT OFFICE

2,541,423

TALLY DEVICE

Mike Kirtogian, St. Louis, Mo.

Application April 30, 1949, Serial No. 90,595

1 Claim. (Cl. 235—127)

1

The present invention relates to novel improvements in devices of the type whereby a summation of numerical units may be visibly exhibited by mechanical means, manually operable.

More specifically, the invention pertains to a novel and compact device incorporating manually operable means whereby any sum or total, ranging in value from 0 to 9999 may be quickly and accurately exhibited.

I am aware that prior to this invention, game counters and mechanical scorers have been patented. Each of them however, is designed to meet the specific scoring requirements of a particular game, principally a card game, such as whist, bridge, and so on.

Except for the particular game for which they are especially designed, these devices have little or no utility.

An object of the present invention is to provide a device which may be employed in score-keeping of any and all games, whether of the playing card variety or otherwise.

A further object is to provide a device which has general utility entirely unrelated to games of amusement, and the like. That is to say, the numerical range of the present device is such that each and every total from 1 to 9999 may be quickly and easily registered thereon, so that its uses for addition, subtraction, or multiplication, are unlimited, as will appear.

In a general summary, the invention may be said to comprise a device preferably of plastic, the predominant elements of which are of two contrasting colors. It thus includes a rectangular block or base member, and top and bottom cover plates therefor of one color, and in the embodiment illustrated, twenty indicator or key members of another color. The key members are positioned either singly or in groups of four. The numerical value of the individually mounted keys, and the numerical value of one of each of the keys mounted in groups is visibly indicated thereon in a color contrasting to that of the keys themselves, preferable in a color corresponding to that of the base block and covers aforesaid. One half of said key members is rotatably mounted on a first stationary and longitudinally extending rod, and the other half of said keys on a second similar rod. Novel resilient spring means are provided for said key members in order to selectively maintain each of them in either a horizontal, or a vertical position.

Features and advantages inherent in the invention which have not thus far been specifically designated, should be apparent from the follow-

2

ing description given in connection with the accompanying drawing, wherein is illustrated the preferred embodiment thereof.

In said drawing:

Fig. 1 is a top plan view of the device comprising the present invention, all of the indicating key members being disposed in a horizontal plane, which is the position each of them occupies when the device is not in use;

Fig. 2 is a similar view with three of the indicating key members disposed in a vertical plane to indicate visibly a certain total;

Fig. 3 is an end elevational view of Fig. 2;

Fig. 4 is a transverse vertical sectional view on an enlarged scale taken on line 4—4 of Fig. 2;

Fig. 5 is a longitudinal vertical sectional view on an enlarged scale taken on line 5—5 of Fig. 1;

Fig. 6 is an enlarged top plan view of the spring element associated with each of the four singly mounted indicator keys;

Fig. 7 is a similar view of the spring element associated with each of the four banks or groups of such keys;

Fig. 8 is a top plan view on a reduced scale of 25 the base member per se.

In Figs. 1, 2, and 3, the device comprising the present invention is generally indicated by the reference numeral 12. It includes a rectangular base member or block 14, a top cover plate 16, and a bottom cover plate 18. Preferably, but not necessarily, these three components are of plastic material, and of the same color, for example black or dark red.

As shown in Figs. 4, 5, and 8, the block 14 includes a left side wall portion 20, a right side wall portion 22, end wall portions 24 and 26, and a longitudinally extending central wall portion 28, all integrally formed.

To the left of the longitudinal centerline there-40 of, the block 14 has formed therein a first opening 30, a second opening 32, a third opening 34, and a fourth opening 36. To the right of said centerline, the block has also formed therein a similar series of openings 38, 40, 42, and 44.

Coextensive longitudinally with each of the openings aforesaid, the central wall portion 28 is dished out as at 46 to provide an arcuate cavity, the purpose of which will appear. Also, coextensive longitudinally with each of the openings aforesaid, the side walls 20 and 22 are beveled as at 48, and are notched as at 49.

As seen to best advantage in Fig. 8, the block 14 has formed therein two longitudinal series of aligned apertures 52, each series being equidistant 55 from the centerline. The apertures 52 are dis-

posed in a plane which may be said to be substantially flush with the upper surface of said block.

The peripheral configuration of the top and bottom cover plates 16 and 18 is identical with that of the base block 14, as shown. The plate 18 is a solid member, but plate 16 is provided with notches 54 to the left and to the right of its longitudinal centerline in such manner, that said notches are in registry with the openings 30, 32, and so on, in the base block.

Coextensive longitudinally with each of the notches aforesaid, the cover member 16 is dished out as at 56 to form a continuation of the arcuate cavity 46 adjacent thereto, as shown in Fig. 4.

As previously indicated, the embodiment of the invention illustrated includes twenty indicator or key members, arranged alternately singly, and in groups of four. The keys are preferably, but not necessarily, of plastic material, the color of which is in sharp contrast to that of the block member 14 and its cover plates.

In the assembled device, there are four keys positioned within the opening 30. These four keys, which are designated by numeral 58, each has a value of one unit as visibly indicated on one of them.

A single key 59 is positioned within opening 32, its value of five units being visibly indicated thereon. A group of four keys 61 is positioned within the opening 34. Each of them has a value of ten units as visibly indicated on one of them. Positioned in the opening 36, is a single key 62 having a value of fifty units, as indicated thereon.

The ten keys thus far referred to are aligned to the left of the longitudinal centerline of the device 12, and the total value of them amounts to ninety-nine units.

There is a group of four keys 63 positioned within the opening 38. Each of these, as visibly indicated on one of them, has a value of one hundred units.

Within the opening 40 is a key 64 having a value of five hundred units indicated thereon. A group of four keys 66, each having a value of one thousand units as indicated on one of them, is positioned within the opening 42.

A single key 68, having a value of five thousand units visibly appearing thereon, is positioned within the opening 44.

The last-named ten keys are aligned to the right of the longitudinal centerline of the device 12, and the total value of them amounts to nine thousand nine hundred units.

The configuration of each of the tabulation keys should be manifest from an inspection of Figs. 1 and 4, wherein it is seen that each of them is of substantially triangular contour in vertical cross-section. The normally unexposed face 69 of each key is bevelled on an angle corresponding to that of the bevelled portions 48 of the side walls 20 and 22, as particularly shown in Fig. 4.

Each of said keys also includes a flat face 71, a slightly rounded corner portion 72, and a horizontal aperture 74. Passing through each aperture 74 of the ten left hand keys, and also through each of the left series of apertures 52 of the block 14, is a pivot rod 76, pressfitted at either end in the walls 24 and 26.

Passing through each aperture 74 of the ten right hand keys, and also through each of the right series of apertures 52 of block 14, is a pivot rod 77, also pressfitted at either end in the walls 24 and 26.

With particular reference now to Fig. 6, there is shown in top plan, a resilient member 78 of

spring metal, which includes a horizontal base portion 79 and a normally upwardly inclined reversely bent integral portion 81. Incorporated in the device 12, are four members 78, one being positioned in each of the openings 32, 36, 40, and 44, the edge portion 82 of each of said members being adapted to enter and to be permanently retained within one of the notches 49 with the cooperation of the bottom plate 18, as portrayed in Fig. 4.

With particular reference now to Fig. 7, there is shown in top plan, a resilient member 84 of spring metal, which includes a horizontal base portion 86 and four normally upwardly inclined reversely bent integral portions 88.

Incorporated in said device 12, are four of the members 84, one being positioned in each of the openings 30, 34, 38, and 42, the edge portions 89 of each of said members being adapted to enter and to be permanently retained within a notch 49 with the cooperation of the bottom plate 18.

Normally, one of the upwardly inclined free portions 81 or 83 of the said spring members bears against the beveled face 69 of one of said keys, as portrayed in Fig. 4 on the left, so as to bias such key into a position wherein said face portion engages the correspondingly beveled upper edge 48 of a side wall 20 or 22.

From the foregoing description, and in view of Figs. 1 and 5, it should be apparent that when the device is not in use, the exposed upper surfaces of the twenty keys are flush with the upper surface of the top plate 16. Further, that the preferably rounded free extremities 91 of said keys project laterally a slight distance beyond the side walls 20 and 22, so that each of them may be manually flipped with ease from a horizontal to a vertical position.

It is not deemed necessary to recite the manner in which the device is assembled. However, it is noted that the contiguous surfaces of the top plate 16, the block 14, and the bottom plate 18 are permanently bonded together, preferable by means of a suitable cementitious agent.

In use, the device may be easily and quickly manipulated to visibly register any total up to nine thousand, nine hundred and ninety nine, as heretofore stated. Said total would be indicated with all twenty keys in a vertical position.

Assuming that it is desirable to register a total of one hundred and fifty, one of the keys 63 and key 62 are flipped from their normally horizontal to a vertical position, it being understood that the other eighteen keys are maintained in normal, that is to say, non-registering position, by the action of the resilient members 78 and 84.

Assuming that the device is employed to keep the score of a football team, and further that a touchdown has been made, the key 59 and one of the keys 58 are flipped to a vertical position, thus indicating a score of six points. Should a conversion follow, another key 58 is flipped into a vertical position, thus indicating a total of seven points, and so on.

In a game of cards, for example in pinochle, each player can tabulate his score as the game progresses. Assuming that the player obtaining the bid has a meld of three hundred pinochle together with twenty in diamonds, three of the keys 63, and two of the keys 61 are elevated to exhibit a total of three hundred and twenty points.

Assuming further, that in the play of the cards, said bidder obtains tricks having a total value of one hundred and thirty points, the remaining key 63 is elevated, the two previously elevated

keys 61 are flipped to normal position, and the key 62 is flipped into perpendicular position. Thus a total score of four hundred and fifty points is in evidence.

Assuming that in the course of the following deal, the same player obtains the bid at one hundred and eighty with no meld, and because of failure to accumulate the necessary points in tricks, he is "set" as is understood, one hundred and eighty points are to be deducted from his previous total, so that his visibly presented score now amounts to two hundred and seventy points. This score is quickly presented by the depression of two keys 63, and the elevation of two keys 61, key 54 being allowed to remain in status quo, 15 likewise the other two keys 63.

The appearance of the device 12, when certain of its keys have been manipulated to indicate a total of five hundred and fifteen points, or units as the case may be, is depicted in Figs. 2, 3, and 4. The three keys are perpendicularly disposed to exhibit said total, they being key 64, one of the keys 61, and key 59. Obviously, if one of the keys 58 be now elevated, the indicated total would be five hundred and sixteen, and if thereafter key 68 be elevated, the indicated total would be five thousand, five hundred and sixteen, and so on.

It should therefore be apparent that the instant invention comprises a novel device which may be utilized for numerous purposes beside those specifically set forth above.

In other words, the device may be used to tabulate, within its range, any information desired relative to for example, the number of restaurant patrons who ordered a certain entree after the supply had been exhausted; the number of servings obtained from a beverage container marked with a specified contents volume; the number of spectators who leave a theatre before the final act; the number of responses by telephone to an advertisement appearing in a newspaper; and so on.

Obviously, modifications in the precise details of construction illustrated and described may be had without departing from the principles of the invention.

For example, instead of bonding the members 14, 16, and 18 with cement, these may be secured together by screws at the corners, or otherwise. Also, the central wall 28 may be separately formed, or formed integrally with either the top or bottom cover, and so on.

What I claim is:

A device for visibly indicating by manually operable mechanical means a selected numerical total ranging from 0 to 9999, said device comprising in combination: a base member of rectangular peripheral configuration including a pair of side wall portions, a pair of end wall portions, and a longitudinally extending central wall portion; a first group of openings comprising a first opening adapted to accommodate a group of four key members each having a value of one unit, a sec-

ond opening adapted to accommodate a single key member having a value of five units, a third opening adapted to accommodate a group of four key members each having a value of ten units, and a fourth opening adapted to accommodate a single key member having a value of fifty units, all four of said openings being in alignment and provided in said base on one side of the longitudinal centerline of the device; a second group of 10 openings comprising a first opening adapted to accommodate a group of four key members each having a value of one hundred units, a second opening adapted to accommodate a single key member having a value of five hundred units, a third opening adapted to accommodate a group of four key members each having a value of one thousand units, and a fourth opening adapted to accommodate a single key member having a value of five thousand units, all four of said openings 20 being in alignment and provided in said base on the other side of the longitudinal centerline of the device; a longitudinal rod passing through aligned apertures in said base member and through an aperture in each of the key members on one 25 side of said longitudinal centerline; a longitudinal rod passing through aligned apertures in said base member and through an aperture in each of the key members on the other side of said longitudinal centerline; a top cover plate provided with 30 aligned notches on either side of said centerline corresponding with the openings in said base; a flat rectangular bottom cover plate; an arcuate cavity formed in said central wall coextensive with and in alignment with each aligned opening 35 and notch respectively of the base member and top cover member; a plurality of resilient metallic members each including a fixed flat base portion and at least one free normally upwardly biased reversely bent portion for selectively maintaining each key member in either a horizontal or a perpendicular position; and recesses formed in the bottom faces of said side wall portions to receive the extremities of said fixed base portions of the resilient members whereby in cooperation 40 with said bottom cover plate said resilient members are retained in position.

MIKE KIRTOGIAN.
